UNITED STATES PATENT OFFICE.

EDWARD A. SLYE, OF BURNSIDE, CONNECTICUT, ASSIGNOR TO VEEDER-ROOT INCORPORATED, OF HARTFORD, CONNECTICUT, A CORPORATION OF CONNECTICUT.

SIGNAL DEVICE FOR OIL-PUMP INDICATORS, ETC.

Application filed February 21, 1928. Serial No. 255,931.

This invention relates to indicating devices of the general character of those shown in Letters Patent of the United States No. 1,531,823, dated March 31, 1925, designed particularly for use in connection with gasoline filling pumps and in which the indicating hand or pointer may be advanced by the operation of the pump. It is particularly concerned with the sounding of an audible signal for each delivery of a unit volume of the gasoline or other liquid.

In the operation of such indicators it has been found that the striker or hammer which is intended to sound an audible signal on the delivery by the pump of a unit volume of liquid and is operated by a cam which moves in consonance with the pointer might fail of operation if the movement of the pump should be stopped when the pointer appears to have reached the limit of unitary movement but before the cam has reached a position which will permit the hammer to drop, or otherwise as determined by the initial setting. Not only would there be no sounding of the audible signal in such a contingency, but the signal would be sounded when the movement of the cam is resumed at the next operation and a full revolution of the cam would be necessary to pick up the hammer again. In this manner the audible signal might be sounded at the wrong time or fail to be sounded at the proper time. Moreover the hammer might not be picked up by the cam for a succeeding operation without the return of the operating device to a position which might be impossible. These difficulties are overcome by mounting the operating cam freely on the actuating shaft, connecting it therewith for operation through a pawl and ratchet, and forming the cam so that when the point of release of the hammer is reached, or otherwise as determined by the initial setting, slightly in advance of the pointer, the cam will be driven ahead by the coaction of the spring pressed hammer arm. Thereby the audible signal is sounded slightly in advance of the full movement of the pointer and the cam itself is moved beyond the striking point and is in readiness to be picked up by the pawl in its first succeeding revolution.

The invention will be more fully explained hereinafter with reference to the accompanying drawings in which it is illustrated and in which:

Figure 1 is a view of the indicator in rear elevation, illustrating particularly the device for sounding an audible signal.

Figure 2 is a partial view in section on the plane indicated by the broken line 2—2 of Figure 1.

Figure 3 is a partial view in section on the plane indicated by the broken line 3—3 of Figure 1.

Figure 4 is a partial view in section on the plane indicated by the broken line 4—4 of Figure 3.

In the embodiment of the invention illustrated in the drawings, the several working parts including the dial *a*, the pointer *a*¹, and the pointer supporting shaft *a*², are supported by a suitable metal frame. The indicating devices are actuated, in the operation of the pump, through a lever *c*, shown in Figure 1, in operative engagement with a moving part of the pump mechanism, not necessary to be shown, preferably the shaft or gear by which the rack bar of the pump is actuated, the lever *c* being secured to the shaft *c*¹, which carries a pinion *c*² in engagement with a gear *c*³. The latter is operatively associated through a friction device, with a pinion *c*⁴ which meshes with the internal gear segment *d*. The latter, through operative connections such as are described in said Patent No. 1,531,823, and not necessary to be described herein, actuates the pointer *a*¹, the pointer being driven in a forward direction during the delivery reciprocity of the pump and the segment and being left at rest during the return reciprocity of the pump and segment.

The pointer *a*¹ is connected with the shaft *a*² through a frictional connection indicated at *a*⁵, so that in the resetting operation the pointer may come to rest against the stop *a*⁶ on the dial plate *a*. The pointer is reset to its initial position, after each operation, by devices which form no part of the present invention.

It will be understood that the forward movement of the pointer *a*¹, being directly effected by the pump actuated devices *c*, *c*¹, *c*², *d*, etc., is proportioned to the number of operations of the pump and for each reciprocity of the pump is advanced over one unit of the dial. It is desirable to cause the forward movement of the indicating devices to effect the sounding of an audible signal as the pointer reaches each unit mark on the dial.

This might be effected by the cooperation of a cam fast on its shaft and driven with the pump actuated indicating mechanism and a spring actuated hammer for a gong. If it should happen that the movement of the pointer is stopped before it reaches the position at which the cam referred to, having a sharp drop, releases the hammer and permits it to strike the gong, no signal would be sounded at that time, but might be sounded at the very beginning of the next operation, to the confusion of the customer. To meet this difficulty the cam p which cooperates with the spring actuated hammer p^1 , to permit it to strike the gong p^2 , is mounted loosely on the sleeved shaft q of the usual gear q^1 , which meshes with the pinion q^2 which rotates with the pump actuated indicating mechanism. The gear q^1 carries a pawl r which engages a single toothed ratchet wheel r^1 formed with or on the hub of the cam p and the drop p^3 of the cam is curved back somewhat, as shown in Figure 4, so that when the pointer a^1 , in its forward movement, approaches a unit mark on the dial, the high point of the cam will have passed slightly beyond the tail of the spring pressed hammer p^1 thereby permitting the hammer to strike the gong under the influence of its own spring. At the same time, the spring pressure of the hammer against the curved drop of the cam will drive the cam

forward. Depending upon the initial setting the striking of the gong takes place slightly but imperceptibly before the pointer reaches the exact unit position, but the signal will be sounded and the cam will be in position to be picked up at the next rotation of the pump actuated gear and placed in readiness to lift the hammer and release it at the next operation.

I claim as my invention:

1. In an indicator for oil pumps, etc., the combination of a pointer, pump actuated mechanism for moving the pointer forward, a gong, a spring pressed signal hammer, a hammer operating cam, and operating means between the pump actuated mechanism and said cam including a ratchet and pawl connection, whereby said cam may have a movement independent of the pump actuated mechanism.

2. In an indicator for oil pumps, etc., the combination with a pointer, pump actuated mechanism for moving the pointer forward, a cam operated with the pump actuated mechanism, said cam having its drop curved back and being loosely mounted, a ratchet and pawl connection between the cam and its operating part, and a spring pressed signal hammer for coaction with said cam.

This specification signed this 17 day of Feb. A. D. 1928.

EDWARD A. SLYE.
